UNITED STATES PATENT OFFICE.

GEORGE HENRY CLARKE, OF LEICESTER, ENGLAND.

DESIGN FOR A WHEEL OR TIRE CARRIER.

46,663.

Specification for Design.

Patented Nov. 24, 1914.

Application filed July 31, 1914. Serial No. 854,405. Term of patent 7 years.

To all whom it may concern:

Be it known that I, GEORGE HENRY CLARKE, subject of the King of Great Britain, residing at Leicester, in the county of Leicester, England, have invented a new, original, and ornamental Design for Wheel or Tire Carriers for Motor-Vehicles, of which the following is a specification, reference being had therein to the accompanying drawing.

Figure 1 is a side elevation of a wheel or tire carrier showing my design. Fig. 2 is a

plan view, and Fig. 3 is an end elevation of the same.

I claim—

The ornamental design for a wheel or tire carrier as shown.

In testimony whereof I affix my signature in presence of two witnesses.

GEORGE HENRY CLARKE.
